HEATER ATTACHMENT FOR RANGES

Henry Honer, Los Angeles, Calif., assignor to
 Western Stove Company, Culver City, Calif., a
 corporation of California

Application August 3, 1937, Serial No. 157,129

13 Claims. (Cl. 126—6)

There have been many attempts to incorporate a heater in conjunction with a cooking range, such being for the purpose of heating a kitchen independent of the heat derived from the range in cooking. Some of these provide for a construction of the range itself whereby this forms a housing for a gas or similar radiator. In other constructions a heater has been built into and incorporated with the range, all of which necessitates a considerable change in the design of the range and a special construction making a separate range where it is desired to have the independent heater for a kitchen.

A main object and a characteristic of my invention is that the independent heater is made as an attachment for the range and may be built on the back of a standard range, therefore this does not necessitate any change in the design or construction of the cooking range: and as a manufacturer as a rule does not apply the heaters to all of the ranges he manufactures, the attachment may be made as ordered. In other words, all the ranges are made complete as to the cooking equipment, a certain number of the heaters may likewise be constructed and these may be attached to the ranges as orders are received for the combination range and heater.

Considered more specifically, a characteristic of my invention relates to a heater preferably of a gas type which incidentally may be used either with gas or electric ranges. Such heater is made in the form of a box-like unit with the necessary devices for attaching the heater unit to the back of the range. Therefore the heater unit in the ordinary installation of the range is adjacent the wall and hence is inconspicuous but develops sufficient heat and a convection flow of hot air to adequately heat the kitchen independently of whether much heat is produced by the range or not. In the modern design of ranges these are usually built so that but little heat is either radiated or disseminated in the kitchen by convection, therefore usually reliance for heating the kitchen must be placed on an independent heater. Various details of the attachable heater include the box-like unit with passages for the flow of air upwardly in which one passage is defined by the back of the range and one wall of the inside heater unit. Other passages are defined by the heater unit and an outside casing along the back and the two ends of the heater unit.

Another characteristic and feature of my invention relates to the accessibility of the valves controlling a pilot burner and the main burner

as these may be placed in the range preferably in a space used for a drawer for cooking equipment. Therefore by partly opening this drawer, the valves are readily accessible, however the pilot light at the beginning of cold weather is usually lighted and burns uninterruptedly, this being merely used to ignite the main burner when the cock or valve supplying gas to the burner is opened. Other detail features relate to the discharge of the combustion fumes, these being carried from the auxiliary heater through a smoke pipe or the like and for sake of convenience may be discharged into a fume box which receives the fumes from the oven and from a trash burner where such is used. Thus only one smoke pipe is necessary.

My invention is illustrated in connection with the accompanying drawings, in which:

Fig. 1 is a perspective view of a range viewed from a front corner with the service equipment drawer removed to show the location of the valves for controlling a pilot and main burner and the gas pipes leading to such burners.

Fig. 2 is a rear elevation of the range showing the heater attachment and may be considered as taken in the direction of the arrow 2 of Fig. 4.

Fig. 3 is a vertical longitudinal section on the line 3—3 of Fig. 4 in the direction of the arrows.

Fig. 4 is an end elevation of the range, the heater and illustrating the fume box taken in the direction of the arrow 4 of Fig. 2.

Fig. 5 is a vertical transverse section on the line 5—5 of Fig. 3 in the direction of the arrows.

In the drawings, the cooking range is designated by the assembly numeral 11. This has a front designated generally by the numeral 12, a back wall 13 which includes the back panel 14 which extends upwardly above the cooking top 15 of the range. In the front there is an opening or space 16 for a drawer or the like utilized for housing cooking equipment. The range may be supported in the ordinary manner on legs 17.

The auxiliary heater is designated by the assembly numeral 25 and may be considered as having an outside housing formed by the back wall 26, a closed end 27, an opposite end 28 having a door opening 29 with a door 30. The other side of the heater unit is defined by the back 13, the ends being secured to this back wall of the range in any suitable manner. This leaves a box-like construction open at the bottom indicated at 31 and having openings at the top hereinunder defined. The inside heating unit designated by the assembly numeral 35 may be considered as having an inner longitudinal wall 36, an outer

longitudinal wall 31, an end 38, an opposite end 39 which is provided with a casting 40 or the like with a window 41 and an ignition opening 42, this being closable by a damper cover 43. The 5 heater proper has a closed horizontal top wall 44, this having an opening 45 from which a fume pipe 46 extends vertically. There is also a bottom wall 47, this wall having openings for the burners 48, of which two are shown (not Fig. 5), these 10 being provided with burner tips 49.

The interior construction of the heater unit 35 includes a vertical baffle 50 extending between the walls 36 and 37 and upwardly from the bottom 47 at the end of the burners and a horizontal lower baffle 51 leaving an opening 52 at one end. This baffle is illustrated as having an inclined section 53 and a horizontal section 54. Above this there is an intermediate baffle 55 leaving a space 56 at one end and thereabove there 15 is an upper baffle 57, there being a space 58 at one end. This baffle has an upturned end 59 secured at 60 to the top 44. It will be understood that these three baffles extend between the vertical walls 36 and 37.

20 This construction with the air openings at the burners provides a first combustion space 65 above the burners leading to a first lower space 66 for the passage of flames. Above this there is a lower intermediate space 67, an upper intermediate space 68 and a top space 69. The flow of the flames and the combustion gases is indicated by the arrows, the products of combustion passing outwardly through the pipe 46. The passages for the heated air include a longitudinal passage 75 25 between the back wall 13 of the range and the wall 36 of the inside heating unit, the cold air entering at the open bottom 31 and being discharged at the long opening 76. There is also another long air passage 77 defined by the back 30 wall 26 of the heater unit and the wall 37 of the inside heater. This also receives the cold air through the open bottom 31 and discharges it at the opening 78. At each end there is also a vertical passage such as 79 defined by the end 35 wall 27 and the end 38 of the inside unit, the cold air entering at the bottom and being discharged at the opening 80 at the top. Another air space 81 is back of the end wall 28 having the door, this being normally closed and has an outlet 82 40 at the top. It will thus be seen that an adequate 45 heating surface is provided for the air flowing upwardly through the various spaces and this is discharged at the top and thus disseminated through the kitchen.

50 Another feature of my invention relates to the convenience for lighting and controlling the heater in that a gas supply manifold indicated at 55 of Fig. 1 may be provided in the compartment 66 which as above designated is for a drawer or the like, in which cooking equipment may be stored. The pilot gas pipe 86 leads from the manifold to the pilot burner and this has a control cock 87, the gas pipe 88 to the main burner has its own control cock 89. These pipes lead 60 downwardly to the bottom of the range proper and are then carried rearwardly to the burners in any suitable manner. The burners and the air supply therefor are of the usual construction. It will therefore be seen that a control of the 65 heater after igniting the pilot flame may be entirely from the front of the range, it being only necessary to open the service drawer to afford access to the valve 89.

The fume outlet pipe 46 may be readily connected to a fume box designated 100 which is

part of the equipment of the range, this box being indicated as having a bottom wall 101, a sloping top 102, opposite ends 103 and 104. It also has a vertical back wall 105 and a front wall 106. The main smoke or flue pipe 107 takes off from the upper part of the fume box and leads to a chimney or the like. The flue pipe 46 is illustrated as entering through the bottom 101. The particular fume box illustrated has a connection 108 from the oven of the range or other parts of 10 the range proper from which it is desired to conduct the fumes out of doors and there is also illustrated a connection 109 to a trash burner or the like built into the range as many ranges have this equipment. With this construction using 15 the fume box 100 above the heater attachment, such box causes a lateral spreading of the hot air as well as functioning to carry off the fumes from the heater.

20 It is believed it will be therefore obvious that this heater in the form of a gas heater may be attached to a cooking range whether this is for instance a gas, electric or coal operated range. It is also obvious that for conditions in which electric current is comparatively inexpensive, an 25 electric heating unit could be substituted for the gas and built in as an attachment on the back of the range.

Various changes may be made in the details of the construction without departing from the 30 spirit or scope of the invention as defined by the appended claims.

I claim:

1. A cooking range having a back wall combined with a heater assembly, said assembly having a back wall spaced from the back wall of the range by two vertical end walls, said end walls being attached to the back wall of the range, an inside heating unit having inner and outer walls parallel to the back wall of the range and two 40 end walls and having a bottom and a top with a fume pipe connected to the top and having a heating unit in the bottom, there being a space between the inner wall of the inside heater and the back wall of the range, a second space between the outer wall of the inside heater and the back wall of the heater assembly and two end spaces adjacent the end walls of the inside heater, said spaces being adapted for the upflow of air heated by the inside heater. 45

2. A cooking range as claimed in claim 1, the inside heater having as a heating unit gas burners with spaces for the inflow of air, a series of baffle plates connecting the inner and outer walls of the inside heater and providing end spaces to 50 develop a zig-zag path for the products of combustion from the burner to the fume pipe.

3. A cooking range as claimed in claim 1, the range having a space opening from the front with a gas pipe having a valve, the valve being 55 located in the said space, the heater unit having a gas burner and the said pipe communicating with said burner.

4. In a device as described, an auxiliary heater having a housing with a back and two end 60 walls and open at the bottom and top, an inside heating unit having inner and outer walls spaced apart and also spaced from the back wall of the housing, the housing and inside heater having means for attachment to the imperforate back 65 wall of a cooking range and thereby provide a first space between the heater unit and such back wall and a second space between the heater unit and the imperforate back wall of the housing for upflow of heated air. 70

5. In a device as described and claimed in claim 4, the inside heater unit having two end walls spaced from the end walls of the housing having a closed bottom except for a gas burner with an 5 air inlet and being provided with a closed top with a fume pipe, there being spaces for upflow of heated air between the ends of the heater unit and the ends of the housing.

6. In a device as described, an auxiliary heater 10 having a housing with a vertical backwall and vertical end walls open at the top and bottom, the end walls being adapted for attachment to the back wall of a cooking range, an inside heater unit having inner and outer walls spaced apart 15 and parallel to the back wall of the housing but spaced therefrom, the heater unit also having vertical end walls spaced inwardly from the end walls of the housing having a closed top with a fume pipe and a closed bottom except for gas 20 burners with an air inlet whereby spaces for upflow of heated air are provided between the heater unit and the walls of the housing and between the heater unit and the imperforate back wall of a cooking range to which the heater unit is 25 attached.

7. A cooking range having a back wall, a fume box positioned back of the said back wall and spaced therefrom with connections to remove fumes from the range and an outlet or discharge 30 flue pipe combined with an auxiliary heater having an outer casing and inner heating unit, the casing having means for attachment to the back of the range and positioned below the fume box, a heater element in the unit, the casing and the 35 unit providing a space for the upflow of air to be heated, one of said spaces being between the back wall of the range and the heating unit, the space between the fume box and the back wall of the range being adapted for the upflow of 40 the heated air from said latter space, the fume box forming a deflecting medium for the hot air from the other spaces.

8. A cooking range having a back wall, a fume box positioned back of said wall and spaced 45 therefrom with connections to remove fumes from the range and an outlet or discharge flue pipe combined with an auxiliary heater, said heater having a housing with a back wall parallel to the back of the range and two side walls connected to the back wall of the range, an inside 50 heater having sides spaced apart in parallel to the back of the housing and to the back of the range and having end walls spaced from the end walls of the housing, thereby providing spaces 55 for upflow of air, one of said spaces being de-

fined by the back wall of the range and one of the walls of the heater, the heater having a flue pipe extending into the fume box, the space between the fume box and the back wall of the range being adapted for upward flow of hot air, 5 the fume box being positioned relative to the heater to deflect the air laterally flowing upwardly through the other spaces or passages.

9. A cooking range having a back wall and an open space from the front adapted to receive a 10 drawer or the like combined with an auxiliary gas heater attached to the back wall of the range with gas pipes secured to the range and having valves positioned in the said space whereby said valves may be readily accessible from the front 15 of the range.

10. A cooking range having a cooking top and an imperforate back wall extending downwardly from the rear edge of the cooking top combined with a heater assembly, said assembly having an 20 internal heater with walls and surrounding casting walls defining between the casing walls and the internal heater passages for air to be heated, one of said passages being defined by the internal heater and the imperforate back wall of the 25 range.

11. A cooking range as claimed in claim 10, the internal heater having a gas burner adjacent the bottom and a fume pipe at the top, the range having a fume box positioned back of the back 30 wall and having a smoke outlet, the said fume pipe entering the said fume box.

12. A cooking range having a cooking top and an imperforate back wall extending downwardly from the rear edge of the cooking top combined 35 with a heater attachment, said attachment having a casing structure attached to the said back wall and open at the bottom and top, an internal heater located within the casing structure and provided with a gas heating element in the bottom with a fume outlet at the top, there being spaces between the internal heater and the casing structure for the upflow of heated air and a space between the imperforate back wall of the 40 range and the internal heater for the upflow of 45 heated air.

13. A cooking range as claimed in claim 12, the range having a fume box positioned back of the back wall of the range and spaced therefrom and having fume connections from an oven 50 and smoke connections from a trash burner and with a smoke or flue pipe outlet at the top, the fume pipe of the heater being connected to and discharging into the said fume box.

HENRY HONER. 55
